US0D1110714S

(12) **United States Design Patent** (10) **Patent No.:** **US D1,110,714 S**
(45) **Date of Patent:** **** Feb. 3, 2026**

(54) **WALLET**

(71) Applicant: **The Ridge Wallet LLC**, Santa Monica, CA (US)

(72) Inventor: **Daniel Kane**, Agoura Hills, CA (US)

(73) Assignee: **The Ridge Wallet LLC**, Santa Monica, CA (US)

(**) Term: **15 Years**

(21) Appl. No.: **29/813,530**

(22) Filed: **Oct. 29, 2021**

(51) **LOC (15) Cl.** **03-01**

(52) **U.S. Cl.**

USPC **D3/247**

(58) **Field of Classification Search**

USPC D3/247, 249–250, 253
CPC ... A45C 11/182; A45C 1/06; A45C 2001/065;
A45C 2001/067; A45C 2001/062; A45C
2011/186

See application file for complete search history.

(57) **CLAIM**

The ornamental design for a wallet as shown and described.

DESCRIPTION

FIG. 1 is a rear perspective view of a wallet;

FIG. 2 is a rear view thereof;

FIG. 3 is a front view thereof;

FIG. 4 is a top view thereof;

FIG. 5 is a bottom view thereof;

FIG. 6 is a left side view thereof; and,

FIG. 7 is a right side view thereof.

The broken lines showing screw holes are for the purpose of illustrating portions of the wallet and forms no part of the claimed design.

1 Claim, 4 Drawing Sheets
